CLAIM

The ornamental design for a kitchen tool, as shown and described.

DESCRIPTION

FIG. 1 is a left side elevation view of a kitchen tool showing my new design, wherein the right side elevation view is a mirror image;

FIG. 2 is an enlarged left side elevation view of the kitchen tool, wherein the shaft is shown broken to indicate further length, the right side view being a mirror image thereof;

FIG. 3 is an enlarged rear elevation view of the kitchen tool, wherein the shaft is shown broken to indicate further length;

FIG. 4 is an enlarged front elevation view of the kitchen tool, wherein the shaft is shown broken to indicate further length;

FIG. 5 is a bottom plan view of the kitchen tool; and,

FIG. 6 is a top plan view of the kitchen tool.
